UNITED STATES PATENT OFFICE.

LEWIS G. FRITZ, OF McCUTCHENVILLE, OHIO, AND ALFRED A. HERZBERGER, OF INDIANAPOLIS, INDIANA.

THREAD-CUTTER.

1,348,276.

Specification of Letters Patent. Patented Aug. 3, 1920.

Application filed September 5, 1919. Serial No. 321,786.

To all whom it may concern:

Be it known that we, LEWIS G. FRITZ and ALFRED A. HERZBERGER, citizens of the United States, and residents of McCutchen-
ville, in the county of Wyandot and State
5 of Ohio, and Indianapolis, in the county of Marion and State of Indiana, respectively, have invented certain new and useful Im-
provements in Thread-Cutters, of which the
10 following is a specification.

Our invention is an improvement in
thread cutters, and has for its object to pro-
vide a device of the character specified,
preferably mounted upon a finger ring and
15 having means for cutting the thread, cord
or the like, so held that there is no possi-
bility of injury to the wearer, and having
means for guiding the thread into the cut-
ter.

20 In the drawings:
Figure 1 is a perspective view of the im-
proved cutter;

Fig. 2 is a side view showing the cutter
and a portion of the ring;

25 Fig. 3 is a front view;
Fig. 4 is a view similar to Fig. 1, show-
ing a modified construction;

Fig. 5 is a vertical section through the
cutter.

30 In the embodiment of the invention
shown in Figs. 1 to 3, inclusive, the cutter
is in the form of a blade 1 which is held
in a substantially U-shaped sheath 2, the
side walls of the sheath being cut away near
35 one end, as indicated at 3, to expose the
cutting edge of the blade at this point and
a portion of the blade itself.

The cutter is preferably mounted upon a
ring 4 of suitable material and size, the
40 said ring being a split ring as shown. At
one of its ends the ring has an up-turned
lug 5 and this lug may be continuous with
the sheath, or it may be soldered thereto as
may be desired. In the present instance the
45 lug, that is, the ring, is integral with the
sheath. The ring has a struck up lug 6 ad-
jacent to the cut away portions 3 of the
sheath, and this lug is split to receive the
blade. The lug inclines upwardly and out-
wardly, fitting against the rear end of the

cut away portions 3 and the said lug acts
as a guide to guide the thread or cord to
the cutter.

In the embodiment of the invention shown
in Figs. 4 and 5 the blade 7 is held in a 55
sheath 8 and the sheath is supported by a
split ring 9. The ring has a struck up lug
10 which is split to receive the blade at the
cut away portions 11 of the sheath, and the
said lug 10 acts to guide the thread or cord 60
to the blade. At each side the sheath is
provided with extensions 12 at the rear ends
of the cut away portions 11, and these ex-
tensions pass through an opening 13 in the
ring 9. The extensions are then bent out- 65
wardly and upwardly upon the inner face
of the ring, as shown in Fig. 5, to hold the
sheath to the ring. The sheath in the pres-
ent instance is integral with one end of the
ring, although it is obvious that it might 70
be separate therefrom and secured thereto
in any suitable or desired manner. The ar-
rangement of the device on a finger ring,
which may be worn upon any finger, insures
that it is always at hand when needed and 75
in convenient position to apply.

The device is especially suitable for seam-
stresses, clerks and the like, and may also
be used for cutting cloth instead of scissors.
The provision of the split ring permits a 80
degree of adjustment, and it will be under-
stood that all of the parts may be of any
suitable or desired material.

We claim:

85 A thread cutter comprising a split ring
for engaging the finger, one end of the ring
having integral therewith an extension bent
over upon the outer face of the ring and
shaped to form a sheath, a blade held in
the sheath, the sheath being cut away on 90
the edge adjacent to the face of the ring
and near the end remote from the connec-
tion with the ring to expose the cutting edge
of the blade, and a support for the sheath
at the cut away portion, said support hav- 95
ing an inclined surface for guiding the
thread to be cut toward the blade.

LEWIS G. FRITZ.
ALFRED A. HERZBERGER.
